CABLE ACTUATED WRENCH

Joseph P. Schwartz, St. Paul, Minn.

Application May 17, 1948, Serial No. 27,489

3 Claims. (Cl. 81—58)

1

My invention relates to an improvement in a cable actuated wrench wherein it is desired to provide a device which may rotate a nut or the like to attach or detach the same.

Many wrenches have been produced which are capable of rotating a nut or similar element in either direction without disengaging the wrench from the nut during operation. Such wrenches usually operate in the manner of ratchet wrenches and rotate a nut or the like a distance equal to or somewhat less than the distance of rotation of the wrench. In some instances it is difficult to rotate a wrench about the axis of the nut to tighten or loosen the same. Furthermore, where nuts must be threaded upon long bolts or the like, considerable time and effort is spent in accomplishing this result.

It is the object of the present invention to provide a wrench including an elongated handle element having a rotatable element at one end thereof. Means are provided for rotating the rotatable element without rotating the handle, thus greatly simplifying the attachment or detachment of the nut or other threaded element.

A feature of the present invention lies in the provision of an elongated handle having a rotatable element at one end thereof and a longitudinally movable operating member at the other end thereof. By pulling the operating member longitudinally of the handle the rotatable element is rotated in one direction. By moving the operating element in the opposite direction longitudinally of the handle the rotatable element remains stationary.

A feature of the present invention lies in the provision of a rotatable element which may accommodate a nut or the like directly or may accommodate a socket either directly or connected thereto through a suitable extension member. Thus while the rotatable member itself is incapable of fitting nuts of various sizes and shapes, it may accommodate suitable sockets or attachments which are capable of fitting nuts of various sizes and shapes. Thus my wrench is capable of rotating any bolt head or nut within reasonable limits through the use of suitable adapters and fixtures.

A feature of the present invention lies in the provision of a rotatable member having a flexible cable wound thereabout by means of which the rotatable element may be rotated. Means are provided for tightening this cable about the rotatable member when the cable is pulled in one direction, thereby causing rotation of the rotatable member by a longitudinal movement of the cable.

2

A further feature of the present invention lies in the provision of an elongated handle having a rotatable member at one end thereof, in the provision of a means of rotating the rotatable member by a longitudinal movement of the operating member, and in providing a brake for preventing a reverse movement of the rotatable member upon a reverse movement of the operating member.

10 These and other objects and novel features of my invention will be more clearly and fully set forth in the following specification and claims.

In the drawings forming a part of my specification:

15 Figure 1 is a perspective view of my wrench showing the general construction thereof.

Figure 2 is a side elevational view partially in section showing the interior structure of the wrench, the section being indicated by the line 2—2 of Figure 3.

20 Figure 3 is a top plan view of the wrench with the covering elements removed to expose the interior construction, certain parts of the wrench being shown in section.

25 Figure 4 is a view similar to Figure 3 showing the operating parts in a different relative position.

Figure 5 is a view similar to Figures 3 and 4 showing the parts in still a different operative position.

30 Figure 6 is a sectional view through the wrench, the position of the section being indicated by the line 6—6 of Figure 2.

Figure 7 is another sectional view through the wrench, the position of the section being indicated by the line 7—7 of Figure 2.

The tool A includes an elongated handle element which in the form illustrated includes a pair of channel members 10 and 11 arranged in opposed relationship. The base 12 of the channel 10 is parallel to the base 13 of the channel 11. The side walls 14 of the channel 10 are in alignment with the side walls 15 of the channel 11. The channels are held in this relation by elongated parallel strips 16 and 17. These strips are secured to the side walls 14 and 15 by cap screws 19 or other suitable means and the strips 16 and 17 project beyond one end of the channels 10 and 11 to form round ended projections 20 and 21 respectively. A U-shaped strip 22 encircles the projecting ends 20 and 21 and the ends of the U-shaped strip are anchored to the bases of the channels 10 and 11 by cap screws 23 or other suitable means.

35 A rotatable spool 24 is supported by the projecting ends 20 and 21 of the body forming strips

16 and 17. As indicated in Figure 7 of the drawings the rotatable element 24 comprises a generally cylindrical body 25 having the center peripheral flange 26 intermediate its ends. The ends of the body are reduced in diameter as indicated at 27 and 29 to fit through apertures 30 and 31 in the strip ends 20 and 21. The apertures 30 and 31 act as bearings for rotatably supporting the rotatable element 24. A rectangular aperture 32 is provided through the spool 24 for accommodation of a nut or bolt head or for the accommodation of an adapter or fixture such as the adapter 33 indicated in Figure 1 of the drawings.

A U-shaped operating element 34 is slidably supported within the handle. The operating element 34 includes two generally parallel sides 35 and 36 and a rounded connecting end 37. The sides 35 and 36 are slidable along the inner surfaces of the channel bases 12 and 13 and are held in place by the side edges of the body forming plates 16 and 17. A U-shaped yoke 39 is supported within the handle body to slide longitudinally thereof. The yoke 39 is generally U-shaped in section and includes upper and lower parallel sides 40 and 41 which are connected by a vertical connecting web 42. A vertical pivot 43 is supported by the plates 40 and 41 and a reel or support 44 is rotatably supported upon the pivot 43. The reel 44 is provided with spaced grooves 45 in its surface for the accommodation of operating cables as will be later described in detail.

A handle end closure 46 extends between the plates 16 and 17 and is anchored thereto. An elongated bolt or cap screw 47 extends through an aperture in the end closure wall 46 and threads into an aligned aperture in the closed end 42 of the yoke 39. By rotating the cap screw 47, the yoke 39 may be adjusted longitudinally of the handle.

A central partition rib 49 connects the plates 16 and 17 intermediate the ends thereof. Suitable anchoring pins 50 hold the partition wall 49 in fixed relation to the handle members 16 and 17. The partition wall 49 acts as a slide guide in the manner which will hereinafter be described.

A flexible cable or similar device 53 is looped intermediate its ends and extended around an anchoring bolt 51 attached to a terminal plate 52. The two ends of the cable 53 wind about the spool 24 above and below the central flange thereon. Preferably the cable winds at least one full revolution about the spool and may wind about the spool two or three times if desired. The ends of the cable then extend longitudinally along the handle in parallel relation and engage in the grooves 45 of the reel 44. The free ends of the cable then again extend longitudinally of the handle in parallel relationship and are anchored to the terminal plate 54 which is parallel to and adjacent the terminal plate 52. The anchoring point of the cable ends of the cable 53 is indicated by the numeral 55.

A reinforcing plate 56 is secured to the end of the arm 36 of the operating member 34. This reinforcing plate 56 is designed to increase the thickness of one end of this operating element. Aligned apertures 57 are provided in the arm end 36, the reinforcing plate 56 secured thereto, and the terminal plates 52 and 54. A pin 59 is supported in these aligned apertures and is held loosely in place by the partition wall 49 and by the base 13 of the channel member 11. The pin 59 is of slightly smaller diameter than the apertures

57 in which the pin is located for a purpose which will now be described in detail.

When a longitudinal pull is exerted against the rounded end 37 of the operating member 34 the portion of the pin 59 engaged in the arm end 36 and the reinforcing member 56 attached thereto is drawn to the right as viewed in Figures 3 and 4 of the drawings. This movement tends to pivot the pin 59 into the position shown in Figure 4 of the drawings and tends to move the terminal plate 54 relative to the terminal plate 52 so as to overlap these plates to a greater extent. This movement tends to tighten the cable 53 about the spool 24 so that movement of the terminal plates 52 and 54 to the right as viewed in Figure 4 will cause rotation of the spool 24 in a clockwise direction.

The pin 59 forms the connecting element between the operating member 34 and the terminal plates 52 and 54. Movement of the operating member 34 in the direction of the arrow in Figure 4 of the drawings tends to tilt the pin 59. This pin 59 acts as a lever to draw the terminal plates 52 and 54 into greater overlapping relation and then acts to move these terminal plates in unison with the operating member 34. As a result the cable 53 is first wrapped more tightly about the rotatable element 34 and then this element is rotated by movement of the terminal plates.

When the operating element 34 has moved to the outer limit of its movement, this element then is pushed inwardly in a reverse direction. Movement of the operating element 34 in the direction indicated in Figure 5 of the drawings tends to tilt the pin 59 in the opposite inclined position, thereby allowing the terminal plates 52 and 54 to overlap a somewhat lesser amount. After the pin 59 tilts into the position shown in Figure 5, further movement of the operating element 34 tends to move the terminal plates 52 and 54 in unison to the left as viewed in this figure.

The tilting of the pin 59 into the position shown in Figure 5 tends to relax the pull upon the operating cable 53, thereby loosening the cable somewhat about the rotatable element 24. This action allows the cable to slide over the surface of the rotatable element so that the rotatable element may remain stationary. A brake element is provided to hold the rotatable member from rotation in a reverse direction. This brake element includes a lever 60 which is pivotally supported at 61 on a mounting bracket 62, Figure 6, connected between the plates 16 and 17. This brake lever 60 is provided with an inclined end 63 which is engageable with the flange 26 of the rotatable element 24 when the rotatable member rotates in a counter-clockwise direction. A spring 64 connected to the partition wall 49 holds the brake lever 60 in engagement with the flange 26.

Thus it will be seen that by engaging the rotatable element 24 with a nut or other element to be rotated it is only necessary to exert a pull on the operating element 34 to rotate the rotatable element in a clockwise direction as viewed in the figures. Rotation of the rotatable element in the opposite direction is prevented during a return reciprocal movement of the operating element 34. Thus the nut or other element engaged may be rotated at a relatively high speed in one direction by successive actuations upon the operating element 34.

Obviously the wrench may be operated in a reverse direction by merely inverting the same.

If the wrench is inverted the upper end of the rotating element will be rotated in a counter-clockwise direction and will be held stationary during return movement of the operating handle.

As previously stated the aperture 32 within the spool 24 may accommodate a suitable adapter extension device or socketed apparatus to fit nuts and bolts of varying sizes. Similarly a screw driver head or other such device may be mounted in the aperture 32 for rotation by the wrench.

In accordance with the patent statutes, I have described the principles of construction and operation of my nut and cap screw starter, and while I have endeavored to set forth the best embodiment thereof, I desire to have it understood that obvious changes may be made within the scope of the following claims without departing from the spirit of my invention.

I claim:

1. A wrench including an elongated housing, a rotatable wrench element rotatably supported at one end of said housing, a pivot supported near the opposite end of said housing, a flexible member looped about said wrench element and said pivot, the ends of said flexible member terminating in spaced relation, an operating element slidably supported by said housing, relatively slidable elements arranged in side by side relation within said housing, each connected at one end to a corresponding end of said flexible member, and a pin extending through said relatively slidable members and supported for movement with said operating element, said relatively slidable members and said operating element having aligned apertures therethrough loosely accommodating said pin, movement of said operating element in one direction tilting said pin in one direction to loosen the flexible member about said wrench element and movement of said operating element in the opposite direction tilting said pin in the opposite direction to tighten said flexible member about said wrench element.

2. A wrench including an elongated housing,

a rotatable wrench element rotatably supported at one end of said housing, a pivot supported near the opposite end of said housing, a flexible member looped about said wrench element and said pivot, the ends of said flexible member terminating in an offset spaced relation, means slidably supported by said housing, said means connecting with the ends of said flexible member and including means for permitting limited longitudinal movement of the ends of said flexible member relative to each other, and operating means connecting with said slidable means for causing sliding movement of said slidable means.

3. A wrench including an elongated housing, a rotatable wrench element rotatably supported at one end of said housing, a pivot supported near the opposite end of said housing, a flexible member looped about said wrench element and said pivot, the ends of said flexible member terminating in a spaced relation, a pair of members slidably relative to the housing and to each other, each of said members being connected to an end of said flexible member, a transverse member pivotally connecting with said pair of members to limit relative sliding between said pair of members, and operating means connecting with one of said pair of members.
